BULLDOZER

Robert G. Le Tourneau, Longview, Tex., assignor
to R. G. Le Tourneau, Inc., Stockton, Calif., a
corporation of California

Application February 13, 1948, Serial No. 144,460

Term of patent 14 years

(Cl. D14—3)

To all whom it may concern:

Be it known that I, Robert G. Le Tourneau, a citizen of the United States, residing at Longview, in the county of Gregg and State of Texas, have invented a new, original, and ornamental Design for Bulldozer of which the following is a specification, reference being had to the accompanying drawing, forming a part thereof.

Fig. 1 is a side elevational view of a bulldozer showing my new design.

Fig. 2 is a perspective view of the bulldozer looking from the front and right side.

Fig. 3 is a similar view looking from the rear and toward the right side.

Fig. 4 is a similar view, looking from the rear and toward the left side.

Fig. 5 is a front end perspective view of the bulldozer.

I claim:

The ornamental design for a bulldozer, as shown.

ROBERT G. LE TOURNEAU.
